(54) **EXCAVATING & REMOVING EARTH**

(76) Inventor: **Nathan Currier**

Nathan Currier Mathew, Mass
Sitter's Patent

The Schedule referred to in this Sitter's Patent and making part of the same containing a description in the words of the said Nathan Currier Mathew of his improvement in a machine to excavate and remove earth.

To all to whom these presents shall come. Be it known that Nathan Currier of Mathew in the County of Essex and Commonwealth of Massachusetts have invented a new and useful improvement in a machine to excavate and remove earth; and that the following is a full and exact description thereof.

The frame of the carriage is placed on two wheels and may be from eight to fourteen feet long, and from four to six feet wide. It may be most convenient if the front wheels are fastened with a bolt or rivet, so they can turn each way under the carriage the front part of vehicle being curved for that purpose.

The front wheels are about two feet in height & the others from two and an half to three feet. The frame is composed of four sticks of timber, two side pieces being what is similar to those of an ox wagon but not straight, one each piece being the rocker resting on the front axle tree, and one on the hind axle tree. The timber is of sufficient size to support the shafts. The front part may have a box to carry tools or not. The frame of the carriage may contain one or three spades as is most convenient. The blade is somewhat similar in form to the common scoper. It is about four feet in length and can be varied according to the carriage. It is fastened to the carriage with bolts and rivets. With nuts or keys passing thru the sides of the blade. Next the blade goes and through the frame is stuck, because as to allow the blade to drop down on the shafts to turn over where the bolts and shafts pass through the blade and frame, there are two strips of iron, one round, the blade and the round the frame to support them and keep them in their place.

The depth of the blade is equal to about one third of its length. It is made of iron iron as a steel, on each side of the blade, near the front is a semi-circular piece of iron, about two thirds of the length of the blade

+ about one half the depth. They are fastened to the frame by iron & brass
pins a bar in the centre which passes up through the cross bar, that leads
from one side of the carriage to the other, and is fastened by keys or pins.
The front part of the frame is connected by chains, running almost per-
pendicularly and fastened to a roller of wood or iron, so as to cause it to turn
the frame at pleasure and to prevent it from turning over. For the purpose
of leading the frame the keys or pins are removed from the centre bar, which
passes through the cross bar and the front edge of the frame, dropped immediate-
ly to the ground. The team is then moved till the frame will sit. It is then
elevated to its proper place by means of a lever or pulley & is there confined
by the keys or pins. The chains are then unfastened and the team driven
to the place, where it is to be unloaded and by a lever and hook or pulley
it is then turned over. The back or front rest or block of wood placed on
the frame of the carriage of sufficient thickness to raise the hind, part to
the same height as the front. Carried part. All your Petitioner claims as
his own invention and not previously patented in the above described. The
carriage is the form of having and arranging the frames together with
the manner of turning them over to unload. He also contemplates cover-
ing parts of the frame to attach the rollers or pulleys so that it may be used
in running carts in deep water.
